(57) **CLAIM**

The ornamental design for a packaging tape dispenser, as shown and described.

DESCRIPTION

FIG. 1 is an isometric view of a packaging tape dispenser according to the present invention;

FIG. 2 is a left side view of the packaging tape dispenser illustrated in FIG. 1;

FIG. 3 is a right side view of the packaging tape dispenser illustrated in FIG. 1;

FIG. 4 is a top view of the packaging tape dispenser illustrated in FIG. 1;

FIG. 5 is a bottom view of the packaging tape dispenser illustrated in FIG. 1;

FIG. 6 is a rear view of the packaging tape dispenser illustrated in FIG. 1; and,

FIG. 7 is a front view of the packaging tape dispenser illustrated in FIG. 1.

The structure depicted by means of broken lines in the figures has been shown for illustrative purposes only and forms no part of the claimed design.
